INVENTOR.
LAURA A. BARNUM

BY Alexander C. Prout, Jr.

ATTORNEY.

UNITED STATES PATENT OFFICE.

LAURA A. BARNUM, OF NEW YORK, N. Y.

GARMENT.

Application filed November 20, 1922. Serial No. 602,211.

To all whom it may concern:

Be it known that I, LAURA A. BARNUM, of New York, New York, have invented certain Improvements in Garments, of which 5 the following description, in connection with the accompanying drawings, is a specification, like characters in the specification and on the drawings designating like parts.

This invention relates to garments and 10 particularly to the adaptation of corsets for surgical purposes, with special reference to affording abdominal support, although I contemplate the use of my improvements in any field for which they are adapted by their 15 nature.

An important object of my invention is to construct the parts of the corset in the environment of the hips in such a manner as to avoid that rigid constraint of the ilium or 20 bony hip formation which is the source of actual torture in many existing types of corsets and in the regulation truss and similar supports as constructed in existing practice.

25 Accordingly I construct my improved garment, comprising usually two opposed sections, as usual in corsets, of a plurality of layers, the outer layer being formed of material provided with stiffening members, and 30 the inner layer, or lining, being formed of elastic material, substantially co-extensive with the outer layer, except at the region of the usual upright stay members, and secured to the outer layer, the latter being interrupted, in accordance with my invention, 35 at the iliac region on each side, so that each ilium of the wearer is confined only by the elastic lining, giving great comfort and ease of movement, whether or not the garment 40 is provided with the supporting devices which I prefer to combine therewith in cases requiring special surgical support, and which I will now describe.

In providing for this portion of my invention I have devised a member, preferably 45 of flat metal, arched to extend higher than the crest of the ilium and of suitable contour to rest snugly at all portions of its surface in contact with the fleshy portions of 50 the wearer's body, having its forward terminus at the lower abdominal zone, low enough to yield an uplift support thereto, while the rearward terminus of this arched member is adjacent to the lower portion of 55 the lumbar region of the wearer, at the

region of greatest strength, somewhat below the waist line.

Preferably one of these members will be provided upon each side of the body, connected respectively in front to any suitable 60 form of pad or other appliance which may be prescribed to fit the area requiring treatment, and to support prolapsed organs and relaxed abdominal walls, such appliance being preferably separate from, and independent of, the corset proper, in front, while the arched supporting members are preferably connected, near their termini, to the back steels or bones of the corset by suitable means, such as a screw stud entering one or 70 another of a series of holes with which the supporting members may be provided for purposes of adjustable attachment.

By this important feature of my invention, the act of lacing the corset is utilized 75 to draw up the depending members and attached appliance with an upward, backward traction, and as the parts are unattached in front the corset can shift with the movements of the body without disturbing the 80 support, whose anchorage at the rear of the corset is at the curved region where there is minimum play of the corset, but nevertheless where there is absolute conformity to the contour of the body, so that firm, 85 unyielding support is secured without interference with fit, and absolutely without the discomfort ordinarily arising from contact with the ilium.

The various features of my invention will 90 be illustrated and described fully in the accompanying drawings and specifications and pointed out in the claims.

In the drawing,

Figure 1 is a view in side elevation of a 95 corset in the construction of which my improvements have been embodied, the same being shown in place upon a wearer.

Figure 2 is a view of the same in rear elevation, showing the anchorage and upward arch of the supporting members; and 100

Figure 3 is a view in front elevation, with the corset members held away from the supporting appliances, showing the independent character of the combined parts when in co-operative relation. 105

In the embodiment of my invention selected for illustration and description to permit ready and complete understanding of my improvements, the part designated by 110

the reference numeral 1 is a corset which may be of any structure and material suitable to carry out the purpose of my invention, and may have any convenient number 5 of parts, one convenient form of corset being that illustrated, in which lower halves or portions, 3 and 5, have at the rear upward extensions 7 and 9, comprising the usual back steels or bones, and laced together as 10 at 11 and from which extend forward independent upper portions 13 and 15, secured at the front by clasps or lacing in usual fashion as indicated at 17 in Fig. 1.

In accordance with an important object 15 of my invention, I prefer to construct the lower halves or sections, 3 and 5, of two plies of material, 4 and 6 respectively, (see Figs. 1 and 3) the ply or layer 4 in each section being formed of material provided with 20 stiffening members 8, while the inner ply or lining 6 in each section is formed of elastic material substantially co-extensive with the outer layer 4, except at the region of the steels or bones 7, 8, and 9, the lining 6 being 25 secured to the layer 4 near its boundary, but substantially free centrally, to afford maximum elasticity, and in accordance with an important object of my invention the layer 4 of each section is interrupted at its 30 central portion, over the iliac region, leaving each ilium of the wearer confined only by the portion of the elastic lining designated by the reference character 10 respectively. The lining 6 may be stitched lightly to the layer 4 around this interrupted region, if desired, but preferably in such a manner as not to 35 interfere with the elasticity of the lining 6.

By this construction I avoid entirely any 40 unhealthful and uncomfortable abrasion or bruising of the iliac region, but by forming the elastic lining 6 substantially co-extensive with the layer 4 I provide for an easy play of the ilium without diminishing its proper support, a provision wholly lacking in garments of a similar character as heretofore 45 constructed and a novel feature which I claim broadly.

In accordance with another important object of my invention, I provide supporting 50 members 21, of any suitable form, material and numbers, of which two are shown in the instance selected for illustration, one for each side of the corset, being made each of a flat strip of flexible spring steel bent in 55 an arch-like curve to mount above the hip and conform to the contour of that portion adjacent to the waist line, resting upon the fleshy parts in order to avoid any contact with the bony hip structure in the region of the ilium.

From this arched portion of the members 21, the rear end of each is extended around 60 to a region of support 23 near the region of greatest strength of the back, and is preferably secured firmly to a sufficiently strong

portion of the corset to yield the requisite stability, and the region of, and means for, this support may vary to suit the exigencies of particular embodiments of my invention.

One convenient mode of effecting the support is to furnish each of the back steels 7 and 9 with a binding screw 27 to pass through one of a series of holes 25 in the members 21 respectively, so that the latter may be firmly connected, each to its respective steel, and this connection may be made effectively upon the outside of the corset, in which case I prefer to provide apertures 29 in the corset sides, to pass the members 21 to the interior, so that in use, the operative forward portions 31 of the members 21 are concealed beneath the lower members 3 and 5, as indicated in Figs. 1 and 3.

By carrying the connecting portions of the members 21 outside the corset, their support and pressure are transferred from the flesh of the wearer's back to the steels which distribute the load, and obviate any discomfort.

In Fig. 3 I have shown the supporting portions 31 connected to a surgical appliance 33, which may be of any suitable character, as prescribed to meet the needs of the wearer, one convenient appliance being the well-known form of pad shown, having two parts, 33 and 34, designed to afford support to relaxed abdominal walls and prolapsed organs, the particular character of this pad forming no feature of my present invention, although the flexible, resilient nature of my attachment members 31, arched out of contact with the bony hip portions, renders my attachment of particular value to use for the support of this appliance.

Means will be provided preferably, in accordance with my invention, to connect the members 31 to the appliance 33, such as screws 36, and any suitable form of connection may be used, the clasp 35 being one convenient form of connector, the connection being accomplished by studs 37 on one portion of the pad, which in the instance illustrated is divided, these studs entering key-hole slots 38 in the clasp 35.

In operation, the members 21 having been 115 passed through the apertures 29 and secured to the back steels 7 and 9 with the binding screws 27 passing through the selected hole of the series 25, as shown in Fig. 2, the wearer will don the corset and while the front thereof is still open, as in Fig. 3, the wearer will proceed to adjust the clasp 35, connecting the supporting portions 31 of the members 21 and the pad parts 33 and 34.

The pad parts 33, and 34 and the supporting members 31 may then be moved to the exact position prescribed, and will be held there by the nature of the arched structure 21 and its connection to back of the corset, but the appliance parts 33 and 34 may, and 130

preferably will, be left quite free from connection with the front portions 3 and 5 of the corset, so that when the lower parts are closed and connected in usual fashion as shown in Fig. 2, and the upper parts 13 and 15 are similarly closed and fastened, as at 17 in Fig. 1, the corset will present the usual appearance, with the supporting portions concealed by the corset but independent of the front portions of the corset, which are free to move with the movements of the wearer, and no constraint whatever is imposed upon the iliac region.

Having illustrated and described my invention thus fully, and suitable means by which the same may be carried into effect, I wish it to be understood that I do not limit myself to the specific form of construction and material selected for illustration and description, nor in general do I limit myself other-wise than as set forth in the claims read in connection with this specification.

What I claim as new and desire to secure by Letters Patent is:—

1. A corset comprising halves each having an outer layer of fabric provided with upright stiffening members at the front and rear and each having an inner lining of elastic material extending from top to bottom intermediate said front and rear stiffened portions, said outer layer having wide horizontal portions of less elastic fabric extending across said elastic lining at the top and bottom to connect said stiffened portions, imparting strength and form-fitting qualities, and said outer layer being interrupted centrally at the iliac region to leave the ilium confined only by said elastic lining, the latter affording elastic support, throughout its length, to the body of the wearer.
2. The combination with a corset comprising halves each having an outer layer of fabric provided with upright front and rear stiffening members, of an attachment comprising a plurality of members of flat, resilient metal secured respectively by adjustable connecting means to the outside of the rear stiffening members of said corset at a region below the waistline, and said flat members having arched portions bent into conformity with the contour of the fleshy supra-iliac region close to the waistline on each side, passing at said arched region through apertures in said corset into the interior thereof and downward to the frontal region below the abdomen, to support the latter, and means to connect said forward portions of said members, in such a manner as to afford uplift support to the abdomen, leaving free the forward portion of the corset-halves, respectively; each of said corset-halves being provided also with an inner lining of elastic material extending from top to bottom intermediate said front and rear stiffened portions; said inner lining being confined at the top and bottom by wide horizontal portions of less elastic fabric, forming part of said outer layer and extending across said lining to connect said front and rear portions with less elastic material, imparting strength and form-fitting qualities; and said outer layer being interrupted centrally at the iliac region to leave said elastic lining free at said region, said lining affording elastic support, throughout its length, to the body of the wearer.

Signed at New York, in the county of New York and State of New York, this 19th day of October, 1922.

LAURA A. BARNUM.
